UNITED STATES PATENT OFFICE.

FREDERICK C. CROFTS, OF CHICAGO, ILLINOIS, ASSIGNOR TO WILLIAM A. PHILPOTT, JR., OF NIAGARA FALLS, NEW YORK.

STITCHING-MACHINE.

1,101,011.

Specification of Letters Patent. Patented June 23, 1914.

Application filed September 21, 1909. Serial No. 518,748.

To all whom it may concern:

Be it known that I, FREDERICK C. CROFTS, a subject of the King of England, residing at Chicago, in the county of Cook and State of Illinois, have invented a new and useful Improvement in Stitching-Machines, of which the following is a specification.

This invention relates to an improved stitching machine for connecting the longitudinal edges of tubular blanks by wire staples for producing knockdown cartons. In machines for this purpose as heretofore constructed the blanks were moved forwardly past the stitching mechanism and after the marginal parts or flaps of the same were stitched together the blanks were again moved backwardly to clear the device which supported the overlapping flaps of the carton and the staple clinching plate. This is objectionable inasmuch as the withdrawal of the stitched blank involves unnecessary handling of the blank and loss of time, thereby reducing the capacity of the machine.

It is the object of this invention to produce a wire stitching machine for this purpose which avoids the necessity of moving the blanks backwardly after the stitching has been completed and permits the blanks to be fed forward continuously to the machine, thereby expediting the stitching operation and reducing the cost of producing the cartons accordingly.

In the accompanying drawings consisting of 2 sheets: Figure 1 is a fragmentary vertical cross section of a stitching machine equipped with my invention, the section being taken in line 1—1, Fig. 4. Fig. 2 is a perspective view of the means for supporting the clencher block. Fig. 3 is a vertical longitudinal section in line 3—3, Fig. 1. Fig. 4 is a fragmentary horizontal section in line 4—4, Fig. 3. Fig. 5 is a fragmentary sectional front view, similar to Fig. 1, showing a reversal of the means for supporting the bar which carries the clencher block.

Similar letters of reference indicate corresponding parts throughout the several views.

My invention is applicable to wire stitching machines of various constructions, that shown in the drawings comprising a horizontal table A, a stitcher head B arranged

above the table and containing the wire sta-

ple forming mechanism, a main supporting arm C overhanging the table from one side thereof and supporting the stitcher head, a pillar D supporting the underside of the table below the stitcher head and mounted on a hanger or bracket E forming part of the clencher arm, and a side gage e arranged lengthwise on top of the table.

The cartons which are operated upon in my improved stitching machine comprise four longitudinal sections f, f¹, f², f³ which are arranged lengthwise and folded into the form of a flattened tube so that the intermediate sections f¹, f² are on one side of the tube and the end sections are on the opposite side of the tube and the longitudinal flap g of one end section laps over the longitudinal flap g¹ of the other end section.

For the purpose of connecting the overlapping edges of the end sections of a carton the latter is placed with its intermediate sections lowermost on top of the table and moved step by step with its overlapping edges lengthwise forwardly over the table

and underneath the lower end of the stitcher head, and during this movement the blank engages one of its longitudinal outer edges with the gage e so as to maintain the overlapping flaps in proper position relatively to the stapling mechanism in the stitcher head. Upon thus moving the carton past the stitcher head while the machine is in operation the staples h are forced downwardly through the overlapping flaps of the carton at such intervals as the operator may elect.

As the legs of the staples pass downwardly below the lowermost one of the overlapping flaps these legs are bent or clenched against the underside of said lower flap by means of a clencher plate or block I arranged below the staple forming a driving mechanism of the clencher head and between the lower part of the tubular carton and the lower one of its overlapping flaps. This clencher plate is secured to the upper side of a flat horizontal supporting bar J which is arranged lengthwise above the table and terminates at its rear end below the stitcher head while its front end is arranged in advance of said head, as shown in Fig. 3.

The supporting bar is suspended in front of the stitcher head by a bracket comprising a vertical web k arranged lengthwise along the edge of the lower flap and connected with the adjacent longitudinal edge 110

of the supporting bar, a horizontal web *l* extending from the upper edge of said vertical web toward the edge of said upper flap, and an arm, body member or hanger *L* preferably arranged vertically and connected at its lower end with the horizontal web *l* outwardly beyond the edge of the upper flap and secured at its upper end to the front edge of the stitcher head, as shown in Figs. 1 and 3, or any other suitable stationary part of the machine.

The means just described for supporting the bar *J* considered by themselves comprise the horizontal web *l* arranged transversely above the bar *J* and parallel therewith, an upright web *k* connecting one longitudinal edge of the bar *J* with the corresponding edge of the horizontal web *l*, and an upright hanger *L* connected at its lower end with the opposite edge of the horizontal web *l* and connected with the main supporting arm *C*. It will be noted that by this means of supporting the bar *J* its front and rear ends are unobstructed rendering it possible to feed a carton with its flaps in an overlapping position continuously forward relatively to the stapling mechanism without interference, thereby avoiding the necessity of moving the carton backwardly after the stitching of its flaps has been completed.

The supporting bar is constructed of resilient material and is normally arranged at sufficient distance above the table top throughout the length of said bar to permit of freely moving the lower part of the tubular carton forwardly between the table top and the supporting bar. When the staple driving mechanism descends, the same depresses the upper and lower carton flaps together with the rear end of the supporting bar *J* until the latter bears against the lower part of the carton and presses the same against the top of the table, thereby supporting the clencher block in position for bending the legs of the staples which are driven downwardly through the carton flaps by the stapling mechanism. As soon as the pressure of the stapling mechanism is removed from the carton flaps and supporting bar, the latter rises owing to its resiliency, thereby permitting the operator to advance the carton another step preparatory to effecting the next stitching operation.

As shown in Fig. 1, the clencher block support is adapted for stapling cartons in which the edge of the uppermost flap faces

the gage *e*. If, however, the carton is to be stitched with the edge of the upper flap facing in the opposite direction, the construction of the bracket is reversed, as shown at *J'*, *L'*, *l'*, *k'* in Fig. 5.

I claim as my invention:—

1. In a machine for stitching overlapping flaps, a guide member for the work comprising a supporting bar, a horizontal web arranged above the supporting bar, a vertical web connecting one of the longitudinal edges of the horizontal web with the corresponding edge of the supporting bar, and a hanger connected with the other longitudinal edge of the horizontal web leaving an unobstructed space above the horizontal web.

2. In a machine for stitching overlapping flaps, a guide member for the work comprising a supporting bar, a horizontal web arranged transversely above the front part only of the supporting bar, a vertical web connecting the inner longitudinal edge of the horizontal web and the corresponding edge of the supporting bar, and a hanger connected with the opposite outer edge of the horizontal web leaving an unobstructed space above the horizontal web.

3. In a machine for stitching overlapping flaps, a guide member for the work comprising a supporting bar, a horizontal web arranged transversely above the front part of the supporting bar, a vertical web connecting the inner longitudinal edge of the horizontal web and the corresponding edge of the supporting bar, a hanger connected with the opposite outer edge of the horizontal web, and a clencher block arranged on the rear part of the supporting bar.

4. In a machine for stitching overlapping flaps, a guide member for the work comprising a work-supporting bar, a horizontal web arranged transversely above the work-supporting bar, a vertical web connecting one longitudinal edge of the horizontal web and the corresponding edge of the work-supporting bar, a body member connected with the opposite edge of the horizontal web, and a clencher block arranged on the work-supporting bar.

Witness my hand this 10th day of September, 1909.

FREDERICK C. CROFTS.
